SLIDING STORAGE RACK

Thomas Shaw, Cranston, R. I., assignor to Stackbin Corporation, a corporation of Rhode Island

Application September 9, 1948, Serial No. 48,412

8 Claims. (Cl. 248—128)

1

This invention relates to a unit rack of the type to be stacked one upon another with each rack adapted to receive one container and in which there is a carriage which may slide from the unit and upon which the container to be stored is located. The slide will move outwardly from the frame a distance sufficient so that the box which is on the carriage may be easily removed therefrom.

Sliding racks of this character have often been provided with rollers to support the slide for easier movement thereof when the loaded carriage is on the slide. Also, a plurality of parts are usually provided in the formation of the rack and slide and this requires assembly of these parts by welding or other securing means.

One of the objects of this invention is to provide a more rugged rack and one which will require less assembly operations in the securing of different pieces together.

Another object of this invention is to provide a frame for the slide which will be of a minimum number of parts.

Another object of this invention is to provide a guide for the sliding carriage which will afford an easy movement of the sliding carriage into and out of the frame and will also limit the movement of the sliding carriage in both of its directions.

With these and other objects in view, the invention consists of certain novel features of construction, as will be more fully described and particularly pointed out in the appended claims.

In the accompanying drawings:

Figure 1 is a perspective view of the rack and sliding carriage extended beyond the rack for a part of its length of its travel;

Figure 2 is a section on line 2—2 of Figure 1;

Figure 3 is a section on line 3—3 of Figure 1; and

Figure 4 is a section on line 4—4 of Figure 1.

In proceeding with this invention I provide units which may be stacked one upon the other, each unit comprising a frame in which there is slidably mounted a carriage to be pulled out of the frame a distance which is a part of the length thereof. The frame comprises a base of sheet stock folded to provide a back and side rails extending therefrom, and these rails are all formed from a single piece of material which is bent at the junction of the rails. The rails are of angular cross-section, each having a vertical wall with inwardly extending flanges to strengthen the vertical walls. The vertical walls of each side rail are provided with an outwardly then inwardly extending portion into which a flange of the carriage extends to limit any upward movement of the carriage which might occur when the carriage is extended beyond the rack. Yokes are located at the opposite ends

2

of the frame side rails which serve as a mounting for additional units upon the top of the unit and serve to provide limits for the carriage flange.

With reference to the drawings, the frame of the unit rack is designated generally 10 and the slide or carriage which is movably mounted in this frame is designated generally 11, and may be moved into a position wholly contained within the frame 10 or may be moved partly out of the frame, such, for instance, as about one-half of the length of the frame.

The frame 10 comprises an angular back rail which has a vertical wall 12 folded at each end as at 13 to provide side walls 14 of side rails extending forwardly therefrom. The back wall 12 is provided with an inwardly extending flange 15, while each of the side walls 14 are provided with inwardly extending flanges 16 which are in the same plane as the flange 15 and are jointed therewith by a miter seam 17. Each of these flanges 15 and 16 is further stiffened by a lip 18 which extends downwardly from the inner edge of the flange 16 such as by bending so that each of these flanges is further stiffened.

At the ends of each of the side rails there are provided yokes of channel shape cross-section such as 19 at the back and 20 at the front end of the frame. The yoke 19 comprises a channel member having a top wall or bridging portion 21 with legs 22, which legs 22 extend along the side walls 14 of the side rails and are flush with the ends thereof. They are secured to these side walls by welding, while across the bottom of the flange 15 and beneath the ends of the legs 22 of this yoke 19 there is provided another channel bar 24 which is welded to the yokes and to the flange 15 and is provided with a means for locking with the upper cross bar 21 of another unit so as to maintain the same in place.

The front yoke 20 comprises a top bar 25 and side legs 26, which legs extend along the outer surface of the side walls 14 of the side rails and have the ends of the side walls 14 bent outwardly to extend along these legs as at 27 in which location they are welded. A generally channel-shaped cross piece 28 extends beneath the ends of these legs 26 and bridges between the side rails. The channel 28 is of a dimension to receive the cross bar 25 of another unit therein so as to hold it in position.

The walls 14 of the side rails at their upper marginal edges are bent outwardly as at 30 at an obtuse angle to the outer surface of the wall 14 and then are bent inwardly as at 31 (see Figure 2) to extend at substantially right angles to the wall 14, thus providing an angular pocket 32 along the upper edge of each of the walls 14. This angular relation extends from yoke to yoke

so that the yokes extend across the ends of this pocket 32.

The carriage designated generally 11 is of angular rail construction and comprises side rails having walls 40 (see Figures 1, 2, and 3) which through the front half of their extent are doubled upon themselves as at 41 (see Figure 3) to stiffen their edges, while at the rear half of their extent, they are flanged outwardly as at 42 (see Figure 2) to extend beneath the portion 31 of the angular pocket 32. The ends of this flange 42 will engage the yokes at either end for limiting the movement of the carriage in either direction, and will also serve to prevent upward movement of the carriage when it is withdrawn from the frame and weight is on the outer end thereof. The ends of the walls 40 are turned inwardly at 43 (see Figure 4) and an end wall consisting of a piece of sheet metal folded upon itself designated generally 44 extends over these inturned ends of the wall 40 and serves to bridge between the walls 40 providing an end wall for the carriage. The walls 40 are also provided with inwardly extending flanges 45 which are strengthened further by downwardly extending lips 46. The edges of the lips 46 closely approach the flange 16 of the frame and provide spaces 51 in which are located anti-friction means for supporting the carriage on the flange 16.

A bar 47 extends between the flanges 45 of the carriage beneath the same, and these flanges are turned downwardly as at 48 so as to provide a mechanical holding of these parts together. Lips 46 terminate at the edge of the bar 47. This bar 47 is bent upwardly at its ends at 49 to extend along the outer surface of the wall 40 and at the ends of this portion 49 the wall 40 is turned outwardly as at 50 to extend across the top of the portions 49 of this bar. The folded-back portions 41 of the wall 40 terminate at the location of the bar so as to engage the edge thereof. The bar is thus fitted in its location at the front end of the carriage.

I claim:

1. A unit rack for a container comprising an open frame and a carriage slidably mounted thereon, said frame comprising front and rear yoke members of generally rectangular form, side rails extending between said yokes at the lower portions thereof for connecting said yokes, each of said rails having a lower horizontal flange portion extending inwardly from the inner edge of the sides of said yokes providing a slideway for said carriage, a vertical wall portion extending between the said sides of the yokes at substantially right angles to said flange portion and with the upper marginal edge portion thereof deflected outwardly and then bent inwardly at the upper edge of the deflected portion to provide an upper horizontal flange portion extending parallel to the said lower horizontal flange portion and with the free edge of the said upper flange portion extending substantially flush with the inner edge of the side of said yokes to provide longitudinally extending pockets closed at the ends by said yokes, said carriage having opposite vertical walls closely adjacent to said vertical wall portions and each extending upwardly to be closely adjacent to the said upper flange portion and having an outwardly projecting horizontal flange extending into said pocket beneath said upper flange portion and adapted to engage the same to prevent relative vertical movement between said carriage and slideway.

2. A unit rack for a container as set forth in

claim 1 wherein the said outwardly projecting horizontal flange on said carriage extends along substantially only the rear half of the said opposite vertical walls, the front end of said projecting flange providing an abutment on said carriage for engaging the said front yoke to limit the outward movement of the carriage.

3. A unit rack for a container as set forth in claim 1 wherein the said outwardly projecting horizontal flanges on said carriage are spaced from both ends of the said opposite vertical walls, the ends of said projecting flanges providing abutments on said carriage for engaging the said yokes to limit the outward and inward movement of said carriage.

4. A unit rack for a container as set forth in claim 1 wherein the ends of said pockets are positioned wholly within the outer and inner edges of the sides of said yokes.

5. A unit rack for a container comprising a frame and a carriage slidably mounted therein, said frame comprising a base member having a rear rail and side rails, said side rails each having a horizontal flange extending inwardly in the same plane providing a slideway for said carriage, said side rails each having a vertical wall at the outer edge of the rail extending in parallel relation to each other and at right angles to said horizontal flange, each of said vertical walls being deflected outwardly at an obtuse angle to the vertical wall to provide an obtuse wall and then inwardly horizontally to provide a horizontal wall and from a longitudinally extending pocket extending a major portion of the length of the side rails, and said carriage having an inwardly horizontal flange overlying the slideway of the base for sliding co-operation therewith and side portions each with a vertical wall closely adjacent said vertical wall of said rail with an outwardly extending flange extending in said pocket and underlying said horizontal wall and slidably related thereto and adapted to engage said horizontal wall to limit the upward movement of the carriage.

6. A unit rack as in claim 5 wherein said flanges on the carriage extend along substantially the rear half of said carriage side walls.

7. A unit rack as in claim 5 wherein said frame also comprises a yoke located at the forward end of said side walls and across the end of said pockets to be engaged by said carriage flanges to limit the outward movement of the carriage.

8. A unit rack as in claim 5 wherein said frame also comprises yokes located at the forward and rear end of said side walls and across the ends of said pockets to be engaged by said carriage flanges to limit the movements of the carriage in opposite directions.

THOMAS SHAW.
